UNITED STATES PATENT OFFICE.

JAKE N. CRASILNECK, OF SAN ANTONIO, TEXAS.

BINDING FOR SHOE-HEEL FACINGS.

Application filed February 23, 1926. Serial No. 99,026.

This invention relates to bindings for shoe-heel facings, is an improvement of the invention set forth in the United States Letters Patent No. 1,540,980, which was issued to me June the ninth, 1925, and has for an object the provision of novel means by which satin, leather, or similar facings for women's shoe-heels may be confined at the lower edge thereof and thus be protected from displacement and injury.

A further object of this invention is to produce an artistic effect at the junction of a woman's shoe-heel and its attached top-lift or cap.

Unlike the invention covered by United States Letters Patent No. 1,540,980, this, my present invention, has no transversely disposed bar from front to rear; nor is the circumference of this invention closed at all its points; therefore, these marked departures make this invention conformable to the external configuration of more than one size of woman's shoe-heel.

The chief object of this, my present invention, is by virtue of its conformable nature to more than one size of woman's shoe-heel, to make unnecessary the manufacture and the handling of so many dies and bindings for shoe-heel facings.

To the end of describing my present invention first briefly and then in detail, reference is hereby made to the accompanying drawings which form a part of this application.

Fig. I shows the improved invention.

Fig. II shows double-pointed nails, a means by which the improved invention may be attached to a woman's shoe-heel.

Fig. III shows a woman's shoe-heel with the improved invention attached between the shoe-heel and the top-lift or cap. The drawing next underneath shows the improved invention when made ready to be attached to a woman's shoe-heel.

Fig. IV shows the improved invention with an alternative form of extended projection (in lieu of arms or wings); also with projections folded back in position to be attached to a shoe-heel.

Fig. I represents the construction of the present invention, which is in the nature of a thin curved metal band or plate so constructed as to be conformable to the external configuration of more than one size of woman's shoe-heel and protect the shoe-heel

facing from displacement and injury; 1 being the band or plate, 2 and 3 being holes for nails or other fasteners, and 1^a one of two places where the bottom of the body has been cut away to permit the two arms or wings in front to be bent back, thus with the open circumference of the invention making it, as hereinbefore stated, conformable to the external configuration of more than one size of woman's shoe-heel.

Fig. II represents a form of double-pointed nails that may be used to attach the invention to women's shoe-heels and top-lifts or caps. Inasmuch as these double-pointed nails do not extend through the top-lifts or caps, use of them will avert damage to floor coverings and floors.

Fig. III represents a woman's shoe-heel with this invention attached between the shoe-heel and its top-lift or cap. No. 5 represents the shoe-heel; No. 1 this invention; No. 6 the top-lift or cap, and No. 4 the double-pointed nails by means of which a woman's shoe-heel, this invention and a top-lift or cap are attached. The lower, smaller drawing underneath Fig. III shows this invention with the two arms or wings in front folded or bent back in readiness to be attached to a woman's shoe-heel. This drawing shows how this invention would appear on the bottom of a woman's shoe-heel before nails are driven in and its top-lift or cap added. The lower edge of the shoe-heel facing (i. e., covering on the shoe-heel) is tucked under, concealed and protected by this invention.

Fig. IV represents a proposed variation in part of this invention, such variation being intended to serve the convenience of a manufacturer. The two arms or wings in the front of this proposed variation consist only of small projections, which projections may be bent back snug against a woman's shoe-heel and then be covered and concealed by the breast (outer covering) that manufacturers place on the inner side (front) of a woman's shoe-heel. The other form of this invention promotes the greater convenience of a shoe repair man inasmuch as a woman's shoe usually comes to him with a breast or outer covering already applied to the shoe-heel. The other (regular) form of this invention is considered better adapted, therefore, for use by repair men, and the proposed variation in the form of this invention is

considered better adapted for use by manufacturers, albeit either repair men or manufacturers may make use of either of the two forms desired.

5 I claim:

1. In a binding for shoe heel facings, a flexible metal band adapted to embrace the heel of a shoe and a facing therefor at the lower edge of the heel, the said band being 10 conformable to the external configuration

of the heel and of a length to project over a portion of the breast face of the heel.

2. In a binding for shoe heel facings, a flexible metal band adapted to embrace a heel and a facing therefor at its lower edge, 15 the said band having extensions foldable across the breast face of the heel, and means for receiving fastenings for securing the extensions to the heel.

JAKE N. CRASILNECK.
